UNITED STATES PATENT OFFICE.

JAMES H. GRADEN AND ZACK E. GRADEN, OF ELLENWOOD, GEORGIA.

OIL BURNER.

Application filed October 27, 1922. Serial No. 527,280.

To all whom it may concern:

Be it known that we, JAMES H. GRADEN and ZACK E. GRADEN, citizens of the United States, residing at Ellenwood, county of Clayton, and State of Georgia, have invented new and useful Improvements in Oil Burners, of which the following is a specification.

This invention is directed to improvements in oil burners and particularly to means for preheating the oil to facilitate the vaporization of the latter into gas for heating or cooking purposes.

An important object of the invention is to provide a vapor-generating device embodying a four-way circuit disposed in the flame zone of the burner and discharging into the fuel chamber, the oil being supplied to the burner through the four-way circuit and thus vaporized into gas without smoke, odor, or formation of carbon.

A further object of the invention is to provide vapor-generating means of the above described character which can be readily applied to the burner as an attachment thereto and as readily removed, when desired, for purposes of cleaning, repairs, or replacement.

With these and other objects in view, which will become apparent as the description proceeds, the invention resides in the construction, combination and arrangement of parts, hereinafter more fully described and claimed, and illustrated in the accompanying drawings, in which like characters of references indicate like parts throughout the several figures, of which:

Figure 1 is a top plan view of an oil burner with the invention applied thereto;

Figure 2 is a view of the burner in side elevation, with a portion broken away to disclose the fuel chamber and air inlet;

Figure 3 is a plan view of the invention as detached from the burner and including inlet and cleaning plugs and nozzle; and

Figure 4 is a view in detail of the needle valve assembly.

Figure 5 is a detail elevation of the needle valve.

As shown in the drawing the burner 10 is of hollow form embodying a fuel chamber 11 into which air is admitted through the bottom opening 12, the fuel escaping from the back end of the chamber into the distributing chambers 13 and 14 extending longitudinally of the burner on opposite

sides. These distributing chambers are provided with a series of slits or flame orifices 15, and a corresponding series of slits 16 are also provided in the top of the burner 60 and forwardly of the front end of fuel chamber 11, as illustrated.

To the structure above described is applied the preheater attachment or four-way circuit member shown in Figure 3. This member consists of a hollow substantially rectangular casing 17, to the front side of which is connected a V-shaped vapor generating tube 18, the side members 19 and 20 of which penetrate the casing 17 at the places 70 shown. At the back or outer side, the casing is provided with a screw-plug 21 having threaded engagement in a clean-out opening 22 in line with tube 19, and an inlet plug 23 registering with the inner end of 75 tube 20. A second clean-out opening and plug may also be arranged in one end of the casing as shown at 24, thus enabling the parts to be very easily cleaned. Extending from the front of casing 17 and centered 80 with respect to the tubes 19 and 20 of the V-shaped member, is a straight tube 25 which constitutes the outlet of casing 17. This outlet tube 25 penetrates the front end of fuel chamber 11 and is provided, at its penetrat- 85 ing end with a nozzle 26 which is detachable, the same having threaded engagement with the end of the tube as illustrated. Then kerosene or other oil is supplied to the burner by way of inlet plug 23, it passes through 90 the four-way circuit provided by tubes 19 and 20, casing 17 and outlet 25, and since these tubes overlie the flame orifices of the burner, being thus well within the flame zone of the latter, it will be seen that the 95 oil will be thoroughly preheated and, hence, supplied to the fuel chamber in such a state as to readily vaporize. The diverting of the oil through a four-way circuit within the flame zone of the burner, subjects the oil to 100 the heat of the burner in a safe and efficient manner and insures its initial preheating prior to its passage to the fuel chamber.

The fuel supply to the chamber 11 is controlled by a long needle valve 27 which ex- 105 tends through a valve guide at the back of casing 17 and through the vapor-generating tube 25, terminating in a tapered point 28 which engages the valve seat 29 in the nozzle 26. The needle valve has an operating han- 110 dle 30 at its outer end and is threaded in- wardly of the handle, as at 31, for engage-

ment with the threads 32 of the packing nut 33 of the valve guide. Nut 33 is threadedly engaged with one end of the guide tube 34 which has its other end screwed into the back of casing 17. Tube 34 engages in a bracket 35 at the front end of the burner and supports the four-way circuit member in position, being itself held in place by a set screw 36.

10 By loosening the set screw and unscrewing tube 34 from the casing 17, the four-way member may be readily removed from the burner, and by further separating the parts as shown in Figures 3 and 4, they may be 15 easily cleaned. The device is likewise adapted to be readily and conveniently replaced, when desired, and in the practical application of the invention may be installed as a built-in or permanent part of the burner or 20 as an attachment to be applied thereto as above described.

In practice, we have found that the form of our invention illustrated in the accompanying drawings and referred to in the 25 above description, as the preferred embodiment, is the most efficient and practical; yet realizing the conditions concurrent with the adoption of our device will necessarily vary, we desire to emphasize that various minor 30 changes in details of construction, proportion and arrangement of parts, may be resorted to within the scope of the appended claims without departing from or sacrificing any of the principles of this invention.

Having thus described our invention, and 35 without enumerating variations and equivalents, what we desire protected by Letters Patent is as set forth in the following claims:

1. An oil burner having a fuel chamber 40 and means for supplying fuel to the said chamber, said means comprising a hollow casing, a V-shaped tube having its ends in communication with the casing, fuel inlet means at one end of the V-shaped tube, an outlet tube extending from the casing and having its outer end penetrating the said fuel chamber, and valve means associated with the said casing and the said outlet tube thereof.

2. An attachment of the character specified comprising a four-way circuit member embodying a V-shaped unit presenting inlet and outlet tubes, a vapor generating tube having a nozzle at its outer end, a connecting casing between the inner end of the vapor generating tube and the outlet tube of the V-shaped unit, a tubular valve guide connected with the said casing in line with the said vapor-generating tube, and a needle valve extending longitudinally of the said guide and generating tube and engaging a valve seat in the nozzle of the latter.
